UNITED STATES PATENT OFFICE.

EUGÈNE MALIVERT, OF PARIS, FRANCE, ASSIGNOR TO HIMSELF AND HIPPOLYTE SAINTAGNE, OF PARIS, FRANCE.

IGNITION-MAGNETO FOR INTERNAL-COMBUSTION ENGINES.

1,334,918.

Specification of Letters Patent. Patented Mar. 23, 1920.

Application filed April 25, 1917. Serial No. 164,383.

To all whom it may concern:

Be it known that I, EUGÈNE MALIVERT, a citizen of the Republic of France, and resident of 17 Rue du Pré-Saint-Gervais, Paris, France, have invented a certain new and useful Improvement in Ignition-Magneton for Internal-Combustion Engines, of which the following is a specification.

The present invention has for its object 10 an improvement applied to high or low tension ignition magnetos for producing sparks at the ignition plugs of internal combustion engines.

It is known on the one hand that in order 15 to obtain the variation of the moment of ignition with a high-tension magnéto, the cam box is displaced angularly so as to break sooner or later the primary circuit and that on the other hand the peak of the 20 tension curve corresponds to a predetermined position of the armature in relation to the pole pieces at the moment when the primary circuit is broken. It follows that it is only in this position of the armature 25 that the spark is at its greatest intensity, and that if the rupture of the primary circuit is made when the armature is in another position, the tension curve, as well as the energy of the spark, is lowered. In magnetos built with a variable advance, the 30 parts are so adjusted that the maximum advance corresponds to the maximum induction effect; this arrangement therefore presents the disadvantage of giving a spark 35 the energy of which decreases step by step as the armature is withdrawn from the pole pieces. This results in serious disadvantages, particularly in starting the motors with the desired retarded ignition and for slow speed 40 running.

In order to obviate this, various constructions have been proposed enabling a spark of the same energy to be obtained whatever be the moment of rupture of the primary 45 circuit.

Notably it has been proposed to displace the magnetic field at the same time as the cam box; it has also been proposed to employ shutters or movable pole pieces within 50 the magnetic field, permitting the poles and armatures to be displaced at the same time as the cam box. This arrangement always insures a maximum of energy in the induction spark, for at the moment when the 55 break takes place the armature is always

at the same distance from the pole pieces whatever may be the position of advance or of retard, but it presents certain difficulties of construction, for in this construction the movable pole-pieces are generally of the same length as that of the fixed pole pieces, and are joined together by cheeks carried in two bearings; this arrangement has the inconvenience of necessitating very great precision, not only in the erection, but also in 65 the mounting of these cheeks to insure that the movable pole pieces turn absolutely concentrically at the same time as the fixed pole pieces and the armature, and that the air gap is always kept very low.

The present invention has for its object a special arrangement and a particular method of mounting the movable pole pieces designed and arranged with a view of getting rid of the disadvantages above referred to.

This invention consists in the employment, in combination with the ignition magnetos, of movable pole pieces characterized by this fact, that they have a width substantially equal to that of the armature core, and that they are received in a circular groove in the fixed pole pieces.

Movement is imparted to these movable pole pieces in any suitable manner; this control may be independent of that of the cam box or may be connected to the latter in order that the displacement of the magnetic field will correspond with the displacement of the armature in the different "break" 90 positions.

The present arrangements of movable pole pieces recessed in the pole pieces of the magnetic field permits the construction of the regulating means to be simplified and of 95 considerably reducing the cost of manufacture.

The annexed drawing shows by way of example the application of the present regulating means to a magneto of usual construction.

Figure 1 is a vertical section of the magnéto.

Fig. 2 is a horizontal section made on the line A—A of Fig. 1.

Fig. 2^a is a detail view, of the armature and the movable pole pieces, the pole pieces being in section.

Fig. 3 is a detail view of one of the fixed pole pieces.

Figs. 4 and 5 show two methods of mounting the movable pole pieces.

Fig. 6 is a detail view.

Fig. 7 shows in vertical section the application of the movable pole pieces for deviating the magnetic flux between the fixed pole pieces.

Fig. 8 shows in vertical section the application of the arrangement for creating a resistance to the passage of the magnetic flux in the armature.

Fig. 9 is a horizontal section made on line B—B of Fig. 8.

Fig. 10 represents on a smaller scale the method of controlling concurrently the movable pole pieces and the cam box.

As is shown in Figs. 1 and 2, the magneto comprises, as usual, magnets *a* upon which the fixed poles pieces *b*, *b*¹ are mounted, and an armature *c* rotating between the latter. In the concave face of each of the pole pieces *b*, *b*¹ is formed a circular groove *b*² for the reception of a movable pole piece *d*, *d*¹. The width of these movable pole pieces *d*, *d*¹ and the groove *b*² in which they are displaceable is substantially the same as that of the core *m* of the armature *c*. See Fig. 2^a. The two movable pole pieces *d*, *d*¹ are united by pieces of non-magnetic metal so as to form a ring. These two pole pieces *d*, *d*¹ may be united, as shown in Figs. 1 and 4, by brass segments *e*, *e*¹ for instance, fixed by riveting or soldering and assembled either by a straight joint as shown in Fig. 4, or by an inclined joint as shown in Fig. 6, or by any other form of joint. Slots *f* are produced in the segments *e*, *e*¹ in order to avoid Foucault currents. An operating handle *g* is mounted upon one of the pole pieces *d*, *d*¹ and passes through a slot *h* in one of the pole pieces *b*¹ and in the magnet *a*, as shown in Figs. 1 and 2. The two pole pieces *d*, *d*¹ may also be mounted as shown in Fig. 5, upon two non-magnetic rings *i*, *i*¹, the spaces between the pole pieces *d*, *d*¹ remaining free. By means of these movable pole pieces *d*, *d*¹ the magnetic field can be displaced at the same time as the primary circuit is broken and one can thus make sure that the flux passing through the armature is always maximum and hence the energy of the spark remains constant both when in the advanced or retarded position.

The pole pieces *d*, *d*¹ by reason of their special disposition have moreover the advantage that when they are partially withdrawn from the pole pieces *b*, *b*¹ they direct the magnetic flux to the central portion of the armature and thus increase the electrical efficiency of the magneto. The ring of pole pieces *d*, *d*¹ may be displaced independently of the cam box controlling the advance or retard of the ignition. When this ring is brought to the position shown in Fig. 7, the pole piece *d* forms a magnetic

path between the two pole pieces *b*, *b*¹ and thus reduces the amount of flux which should pass through the armature. Furthermore, when the ring *d*, *d*¹ is turned as shown in Fig. 8, so that the pole piece *d* is withdrawn, the groove *b*² increases the air gap as is shown in Figs. 8 and 9, and produces a resistance to the passage of the magnetic flux through the armature, so that this flux is no longer directed toward the central portion of the armature. This possibility of diverting the magnetic flux or of forming a resistance enables the magneto to be used under the best conditions at variable speeds.

For each case and for each output the most favorable position of the movable pole pieces relatively to that of the armature at the moment of the break of the primary circuit will be determined in order to obtain the maximum output. The operating handle *g* of the movable pole pieces *d*, *d*¹ may be connected with the operating lever *j* which controls the advance or retard of ignition as shown in Fig. 10.

It will be understood that the above described arrangement is only given by way of example, and that the form, the dimensions, and the details of construction of its constituent elements may be modified according to its different applications.

I claim:

1. In an ignition magneto for an internal combustion engine, fixed pole pieces having a circular groove intermediate of their ends, an armature having pole pieces connected by a core, movable pole pieces, and pieces of non-magnetic metal uniting said movable pole pieces to constitute a ring, said movable pole pieces being interposed between said fixed pole pieces and said armature, and being of a width substantially equal to that of the core of said armature and said ring being received in the circular groove of said fixed pole pieces.

2. In an ignition magneto for an internal combustion engine, fixed pole pieces having a circular groove between the ends thereof, an armature having pole pieces connected by a core, movable pole pieces, and segments of non-magnetic metal uniting said movable pole pieces to constitute a ring and formed with slots, said movable pole pieces being interposed between said fixed pole pieces and said armature and being of a width substantially equal to that of the core of said armature, and said ring being received in the circular groove of said fixed pole pieces.

3. In an ignition magneto for an internal combustion engine, fixed pole pieces having a circular groove intermediate of their ends, an armature having pole pieces connected by a core, a movable sleeve-like member formed of pole pieces and pieces of non-magnetic

metal provided with openings and connecting the pole pieces, pole pieces being interposed between said fixed pole pieces and said armature and being of a width substantially equal to that of the core of said armature, and said sleeve-like member being received in the circular groove of said fixed pole pieces, and means for turning the sleeve-like member.

- 10 4. In an ignition magneto for an internal combustion engine, a magnet, fixed pole pieces on said magnet and having a circular groove, an armature having pole pieces connected by a core, movable pole pieces, pieces 15 of non-magnetic metal uniting said movable pole pieces to constitute a ring, said movable pole pieces being interposed between said fixed pole pieces and said armature, and being of a width substantially equal to that 20 of the core of said armature and said ring being received in the circular groove of said fixed pole pieces, an operating handle mounted upon said ring, an operating lever adapted to control the advance or retard of ignition, and means for connecting said operating handle with said operating lever.

through a slot formed in one of said fixed pole pieces and in said magnet. 25

5. In an ignition magneto for an internal combustion engine, a magnet, fixed pole pieces on said magnet and having a circular groove, an armature having pole pieces connected by a core, movable pole pieces, pieces 30 of non-magnetic metal uniting said movable pole pieces to constitute a ring, said movable pole pieces being interposed between said fixed pole pieces and said armature, and being of a width substantially equal to that 35 of the core of said armature and said ring being received in the circular groove of said fixed pole pieces, an operating handle mounted upon said ring, an operating lever adapted to control the advance or retard of ignition, and means for connecting said operating handle with said operating lever. 40

EUGÈNE MALIVERT.
